UNITED STATES PATENT OFFICE.

ROBERT L. HIBBARD, OF BELLEVUE, PENNSYLVANIA.

BORING LATHE.

1,425,202.

Specification of Letters Patent. Patented Aug. 8, 1922.

Application filed August 26, 1918. Serial No. 251,441.

To all whom it may concern:

Be it known that I, ROBERT L. HIBBARD, a citizen of the United States of America, and a resident of Bellevue, Allegheny County, and State of Pennsylvania, have invented certain new and useful Improvements in Boring Lathes, of which the following is a specification, reference being had to the accompanying drawings, forming a part thereof.

My invention relates to boring machines and has special reference to large horizontal machines of the type in which the boring tool is relatively fixed and the work revolves or vice versa. It furthermore pertains to boring lathes which are particularly adapted for boring guns or rifles of large calibre and great length, and which are necessarily provided with long boring bars.

One object of my invention is to provide a machine of the aforesaid character that shall be constructed and arranged in such manner as to render the usual auxiliary bed or bench unnecessary.

Another object is to minimize the strains on the machine without limiting its swing, by producing a feed screw which acts upon the tailstock relatively close and parallel to the boring bar without extending adjacent to the work.

A further object is to provide a relatively simple lathe structure in which the fixed bar support and its connected members may be readily and quickly adjusted longitudinally of the lathe and fixed to accommodate the length of the work in the machine.

Still another object is to provide an intermediate bar support between the tailstock and the fixed bar support, and means for automatically adjusting its position as the tailstock approaches the fixed bar support or is withdrawn therefrom.

Another object is to provide a simple and improved change gear structure to enable the gears to be quickly and easily changed to meet the desired conditions.

Other objects and advantages of my invention will be hereinafter set forth, and I will now describe the same in detail with reference to the accompanying drawings and set forth the novel features thereof in appended claims.

Referring to the drawings:

Figure 1 is a longitudinal elevation of a boring lathe arranged and constructed in

accordance with my invention and constituting an embodiment thereof.

Figures 2, 3 and 4 are partial elevations corresponding to Figure 1, showing the same machine with its movable parts adjusted to different positions to illustrate the mode of operation.

Figure 5 is an end elevation showing the head stock and change gearing drawn to a larger scale.

Figures 6 and 7 are sectional elevations showing in detail the respective sets of quick change gears which are shown in elevation in Figure 5.

Figures 8, 9 and 10 are detail views of the adjustable stud arms which form parts of the change gear mechanisms.

Figure 11 is a sectional detail view on the line 11—11 of Figure 6.

Figure 12 is a plan view showing a detail of the splined stud shaft and adjustable key of the gear change mechanism.

Figure 13 is a longitudinal sectional elevation of the tailstock and feed screw mechanism.

Figure 14 is a plan view of the same parts.

Figures 15, 16, 17 and 18 are transverse sectional elevations taken respectively on the lines 15—15, 16—16, 17—17, and 18—18 of Figure 13.

Figure 19 is a sectional detail view showing the feed screw motor clutch.

Figures 20 and 21 are detail views of the feed screw driving gears.

Figures 22, 23 and 24 are views of modified structures for effectively adjusting and controlling the position of the intermediate bar support.

Like parts designate corresponding parts in all the figures.

General description.

The boring lathe illustrated, which constitutes an embodiment of my invention, is particularly adapted for boring guns or rifles of large calibre. In general, it comprises a bed 9, a head stock 10, a face plate 11, a driving motor 12, tool carriages 13, a driving shaft 14, a feed screw 15, change gearing 16, a fixed bar support 17, a spaced support 18, a quick return motor 19 mounted thereon, a tailstock 20 which is slidably mounted on the bed between the spaced supports, a boring bar 21, and a movable, intermediate bar support 22.

110

As clearly shown in Figures 1 and 2, the spaced supports 17 and 18 may be affixed to the bed by clamping bolts 23 and 24 while the tailstock 20 and the boring bar are being advanced by the feed screw. It is also possible as shown in Figure 3 to release the supports 17 and 18 so that they are slidable on the bed and to fix the tailstock 20 by clamping bolts 25 or other suitable means. Under these conditions the turning of the feed screw, as more fully described hereinafter, affects the adjustment of the spaced supports 17 and 18 and their attached parts.

The supports 17 and 18 constitute bearings for the feed screw 15 to which they are connected in such manner that they always maintain a fixed relation to each other and follow any longitudinal adjustment of the feed screw section.

20

Change gearing.

The operative driving connection between the spindle 26 of the lathe and the driving shaft 14 will now be discussed in detail, special reference being had to Figures 1, and 5 to 12 inclusive.

Affixed to the head end of the driving shaft 14 is a gear wheel 27, a bushing 28 and a shear pin 29 being interposed to avoid stripping the gears in case of accident, and affixed to the spindle 26 is a pinion 30. A stud 31 extends outwardly from the head stock and has a sleeve 32 rotatively mounted thereon and held in position by nuts 33. A gear wheel 34 is affixed to the sleeve at its inner end and meshes with the pinion 30 on the spindle 26. There are mounted on the sleeve a pair of pinions 35 and 36 of different size and either one or the other of them is active depending on the position of an adjustable key 37. This key is slidably mounted in a spline or keyway 38 in the sleeve 32 and has at its outer end a lug 39 which engages an annular handle grip 40. The movement of the key is limited longitudinally of the sleeve and its extreme positions are accentuated by a ball 41 which is pressed by a spring 43 into engagement with depressions 42 in the sleeve. The sleeve, the key, and the handle are shown on a larger scale in Figures 11 and 12.

Pivottally mounted on the inner end of the stud 31 is a radius arm 45 which has a perforated lug or sleeve 46 at its outer end in which a movable stud 47 is mounted. The inner end of the stud 47 is screw-threaded as shown at 48 and engages a nut 49 which fits into a curved, channel-shaped slot 50 in a fixed bracket 50^a. The curvature of the slot is centered about the axis of the stud 31 so that when the stud 47 is loosened in the nut 49 both parts are free to swing with the arm 45 about the stud 31 as an axis. The stud 47 extends outwardly beyond the arm 45 and supports a sleeve 51

to which a gear wheel 52 is attached and meshes with the pinion 35, the pinion 53 meshing with the gear wheel 27.

The outer end of the stud 47 is square or is otherwise formed at 54 to receive a wrench, nuts 58 being utilized to hold the sleeve 51 in place.

The arrangement of parts is such that the stud 47 can be turned very easily to either fix the stud in position, or to release it so that the arm 45 may be swung and the stud adjusted to another position.

Furthermore, the nuts 55 can easily be removed and the gear 53 removed and replaced by a gear of a different size. The gear 52 will continue in mesh with the pinion 35 because it swings about the center of the gear 35 as an axis.

In order to provide for a quick change in speed for adapting the machine for either a roughing or finishing cut, I have provided a second train of gears which comprise an intermediate gear 56 mounted on an adjustable stud 57 which corresponds to the stud 47 and is interposed between the pinion 36 and the gear wheel 27. The adjustable stud 57 is mounted in a radius arm 58 which swings about the center of the feed screw section 14 as an axis so that the pinion 36 may be removed and replaced when it is desired to change the gear ratio.

Assuming that the gear ratios are chosen as represented in Figures 6 and 7, a change from relatively low speed suitable for a heavy roughing cut, to high speed suitable for a finishing cut, is effected very quickly and easily by means of the adjustable key 37. When the handle 40 is pushed inwardly into the position shown in Figure 6, the key engages the key slot in the pinion 35, establishing the driving connection from the spindle 26 through the gear wheels 30, 34, 35 and 52, 53 and 27 to the feed screw section. On the other hand, if a relatively high speed is desired, the handle 40 is pulled outwardly to the position shown in Figure 7 and the key then engages the key slot in the pinion 36. Connection is thus established from the spindle 26 through gears 30, 34, 36 and 56 and 27 to the feed screw section.

The stud 57 cooperates with a sector slot 59 in a fixed bracket 60 and is adapted to receive a wrench at its outer end so that it can be set in any desired position.

Attention is particularly directed to the fact that it is possible to loosen the stud and make the adjustment without reaching behind any of the gear wheels as is necessary in the usual arrangements of the prior art.

The radius arm 45 is shown in detail in Figure 8 while the radius arm 58 is shown in Figure 9. The formation of the fixed bracket 50^a and the nut which cooperates with the sector slot 50 therein, is clearly

shown in the sectional detail view of Figure 10.

Fixed bar support.

5 The feed screw driving shaft 14 is not necessarily screw-threaded but is splined and has slidably mounted on it a sleeve 61 to which a pinion 62 is secured. The sleeve has an annular slot 63 which is engaged by a
 10 fork 65 on a rack bar 66. The latter is mounted in bearings 67 in the fixed bar support 17. It is adapted to be actuated by a gear segment 68 on a transverse shaft 69, which extends outwardly through a wall of
 15 the support 17 and has a crank arm 70 affixed to it. The arm is provided with a handle 71 and an accentuating pin 72 which is spring pressed into engagement with notches in the casing of the support.
 20 The arrangement of parts is such that when the crank handle is turned in one position the pinion 62 meshes with the gear wheel 73 at the head end of the feed screw section 15 and when the crank arm is moved
 25 to its opposite position the sleeve 61 and pinion 62 are moved into the position shown in broken lines in Figure 13, the pinion being then disengaged from the gear 73. The relation between the gears is determined entirely by the adjustment of the crank arm and is independent of the position of the fixed bar support and of the feed screw sections 14 and 15 relative to each other, the arrangement of parts being such that when
 30 35 the fixed bar support 17 and its connected parts move longitudinally on the bed the sleeve 61 slides but does not turn on the splined feed screw section 14.

Spaced support.

40 The spaced support 18 is formed to provide a bearing 83 for the tail end of the feed screw section 15 and constitutes a support for the quick return motor 19 which is
 45 geared to the feed screw section 15 in any suitable manner. As shown in Figures 13, 18 and 19, the gear wheel 74 is affixed to the feed screw section 15 and meshes with the pinion 75 on a stud 76. Mounted on the
 50 same stud is a gear wheel 77 and a sliding key 78 is provided for the purpose of either coupling the pinion 75 to the stud 76 or releasing the pinion 75 so that it is free to turn on the stud. The sliding gear is structurally similar to the key 37, already described, and is similarly actuated by an annular handle 79.

A gear 77 is connected by gear wheels 80 and 81 to the shaft 82 of the quick return
 60 motor 19. At one end of the bearing 83 is the gear 74 and at the opposite end of the bearing 83 is a gear 84 so that any longitudinal movement of the shaft section produces a like movement of the support 18.
 65 The feed screw 15 is similarly connected

to the fixed bar support 17 so that while the fixed bar support constitutes a bearing for the screw any longitudinal movement of the screw is necessarily transmitted to the fixed bar support. In other words, the feed screw 70 15 is rotatively attached to the spaced supports 17 and 18.

Tail stocks.

The tail stock 20 has a relatively long base 75 85 which is slidably mounted on the bed of the lathe and it is provided with a nut, or screw-threaded bushing 86 which is removably affixed in position by bolts 87. The feed screw 15 is in cooperative engagement with 80 the nut, the arrangement being such that if the feed screw is longitudinally affixed it produces, when rotated, a longitudinal movement of the tail stock on the lathe. The boring bar 21 is affixed at one end to the 85 tail stock and extends toward the head stock through the intermediate bar support 22 and the fixed bar support 17.

Attention is directed to the fact that the feed screw 15 is relatively close to the boring 90 bar and is so arranged that while it is above the bed of the lathe it does not in any way interfere with the work because it does not extend toward the head stock beyond the fixed bar support 17. It is therefore evident 95 that the screw section 15, if desired, may be located even closer to the boring bar than shown in the drawings, with the advantage—that since the forces exerted by the feed screw acting upon the nut 86 to move the tail 100 stock in one direction and the reaction of the boring bar tending to oppose such movement constitute a force couple—the strains upon the tail stock and upon the mechanism are very much reduced by keeping the opposing forces close together. 105

Intermediate bar support.

The intermediate bar support 22 may be omitted if the length of the boring bar is not 110 great relative to its size and on the other hand it may be desirable to provide two or more intermediate supports if the bar is very long. I have illustrated a single intermediate bar support and in this connection 115 I will explain the operation in case more than one is employed.

The support 22 has a sleeve or bearing box 88 through which the boring bar 21 extends and it is provided with a rotatable nut 120 89 which is threaded onto the feed screw 15 as clearly shown in Figure 13. The nut has a flange 90 at one end and a gear wheel 91 at the other so that it is held against longitudinal movement relative to the support, but is 125 free to turn therein. The gear wheel 91 meshes with the gear wheel 92 which is slidably mounted on a spline shaft or spindle 93. The gear 92 has flanges 94 so that it moves on the shaft 93 to correspond with the 130

movement of the gear 91 on the feed screw 15, and always maintains its cooperative engagement with the gear 91. The arrangement is clearly shown in Figures 20 and 21.

The shaft 93 is mounted in suitable bearings 95 and 96 in the fixed bar support 17 and in the spaced support 18, and extends through a bearing 97 in the tail stock. It is provided with a gear 98 which meshes with the gear 84 on the feed screw section 15. The arrangement of parts is such that the shaft 93 is driven at about one-half the speed of the feed screw section 15 and consequently the nut 89 is rotated at about half speed, thereby causing the nut to travel at one-half the speed at which it would travel due to the rotation of the feed screw itself. If it is assumed that the intermediate bar support is centrally located between the tail stock and fixed bar support, as shown in Figure 1, the intermediate bar support and the tail stock are timed to come together as shown in Figure 3, and the intermediate support always maintains a central position as indicated in Figure 2.

If more than one intermediate bar support is utilized the speed of each will be determined according to its position and it will only be necessary to utilize a different gear connection between the shaft 93 and the rotatable nut which is mounted in each intermediate bar support.

In order to make the operation of the intermediate bar support clear it is only necessary to consider the two extremes as follows: if it is assumed that the nut 89 is fixed to the intermediate bar support, the latter will travel at the same speed as the tail stock; if the nut 89 is absolutely free to rotate in the intermediate bar support the latter will remain stationary while the nut will turn instead of being advanced.

It therefore is evident that if the nut is rotated at some speed which is less than that corresponding to the pitch of the feed screw, the bar support will travel at a less speed than the tail stock and the speed at which it moves can readily be determined by gearing.

The arrangement above described has the great advantage of being not only operative as the boring bar is advancing toward the head stock but is automatically operative to return the intermediate bar support to its intermediate position when the boring bar is being retracted.

In Figure 22 I have shown a modified arrangement for causing the intermediate bar support to advance at the proper speed and in which the necessity for an auxiliary shaft such as the shaft 93 is avoided. In this arrangement a driving gear 100 is slidably mounted on the feed screw section 15 which in this case is provided with a spline 101 to cooperate with the gear key 102. The gear 100 meshes with the gear 103 which is affixed

to a gear axle stud or shaft 104 on the intermediate bar support. The gear 105 is affixed to the same shaft or axle and meshes with the gear 91 which forms a part of the nut 89.

The feed screw 15 in this case has the dual function of feed screw and driving shaft for rotating the nut 89 at a lower speed than the feed screw.

This arrangement is not preferred on account of the fact that it necessitates providing a keyway or spline in the feed screw but in many cases this will not be objectionable.

Still another modification of my invention is shown in Figure 23 in which the nut 89 is replaced by the nut 106 which has flanges 107 and is mounted in a tapped hole 108 in the intermediate bar support 22. It is externally threaded to cooperate with the tapped hole and has a low pitch thread relative to the pitch of the feed screw which is usually very high. The nut is also internally threaded to cooperate with the feed screw and in length it is considerably greater than the section of the support through which it extends. The arrangement of parts is such that when the feed screw is first active in advancing the tail stock the intermediate bar support remains stationary and the nut 106 rotates from the position shown in full lines to that shown in broken lines in Figure 23. The pitch of the external threads on the nut are arranged to permit the tail stock to move up to the intermediate bar support while the nut travels from one position to the other. A further action of the feed screw in the same direction cannot rotate the screw 106 because one of the flanges now engages the support and consequently the intermediate bar support advances at the same speed as the tail stock.

This arrangement obviously does not keep the intermediate bar support central between the tail stock and the fixed bar support 17, but it prevents the distance between supports at any time from being greater than that of the retracted tail stock shown in Figure 1. In the reverse operation the nut will rotate and travel from one position to the other relative to the intermediate bar support while the tail stock is being retracted to an intermediate position and then the intermediate bar support will move back at the same speed as the tail stock until it reaches its initial central position.

Operation outlined.

The operation of the complete machine will be readily understood from the operation of the various sections as above described. Attention is, however, directed to the fact that when the suitable gear changes have been made for work of a given type or size the speeds are quickly adjusted for roughing and finishing cuts without removal and change of gears, by shifting the position

of the handle 40. Furthermore, the boring bar tail stock and intermediate support, may be rapidly returned to their initial positions by disconnecting the feed screw 15 from the 5 driving shaft—this being accomplished by swinging the crank handle 71 to the desired position—and coupling the quick return motor 19 to the feed screw 15, by means of the slip gear handle 79. When the parts are in 10 their initial positions the quick return motor 19 is disconnected from the feed screw and the latter is connected with shaft 14 ready for a new cutting operation in which the work and the feed are synchronized or 15 cooperatively dependent in speed.

Machines for the same general purpose, hitherto constructed, comprise a bed on which a large and expensive casting called a bench, is mounted, the tail stock of the 20 lathe being movably mounted on the bench. In this type of construction the bench must be controlled by a feed screw which extends the entire length of the machine and a second screw is employed for adjusting the tail 25 stock on the bench.

My improved structure renders the bench unnecessary, avoids the expense and weight of this member, and provides a simple and effective means for adjusting the tail stock.

Attention is directed to the fact that I use 30 instead of the half-nut usually employed to engage the feed screw and avoid the screw supports in machines of this character—a complete nut 86 at the tail stock 20. The 35 screw is supported on one side of the tail stock by the intermediate bar supports and may be also supported by speed movable screw supports 110 and 111 on the opposite side of the tail stock, as shown in the modification of Figure 24 to which reference may 40 now be had.

As here shown there are two intermediate bar supports 112 and 113 to which the screw supports 110 and 111 are respectively connected. This is accomplished by a bar 114 45 which is affixed at its ends to the intermediate bar support 112 and the screw support 110, and by a tube 115 which loosely surrounds the bar 114 and is affixed at its respective ends to the intermediate bar support 113 and the screw support 111. With 50 this arrangement as the tail stock moves forward from its rear position in operation it encounters the first intermediate bar support which it carries forward with it, the first rear screw support 111 being carried forward at the same time by reason of the connection above described. In the same 55 way the intermediate bar support 112 is carried forward and carries with it the second rear screw support 110.

It is evident that no other means for moving the intermediate bar support is necessary with this arrangement and that one or 60 more intermediate bar supports may be em-

ployed with a corresponding number of connected rear screw supports. Of course, a fewer number of screw supports may be found necessary in which case some, but not all of the intermediate bar supports will be 70 connected to the rear screw supports. Other arrangements will suggest themselves to those skilled in this art.

Structures of preferred form and construction have been illustrated and described 75 for the purpose of showing ways in which this invention may be used, but the inventive thought upon which this application is based, is broader than these illustrative embodiments thereof, and I therefore intend 80 no limitations other than those imposed by the appended claims.

What I claim is:

1. A boring machine comprising a bed, a fixed bar support adjustable thereon, a spaced support also on the bed, a feed screw extending between said supports and rotatively but non-slidably attached to each of them, and a tail stock mounted on the bed between said supports and arranged to constitute a travelling nut relative to said screw. 90

2. The combination with the guide ways of a machine tool, of an adjustable boring-bar unit mounted thereon, said unit comprising a pair of spaced supports adjustably 95 affixed to said guide-ways, a screw shaft maintaining said supports in spaced relation, a tail stock between said supports, and means operatively connecting the tail stock and screw shaft whereby rotation of 100 the latter imparts translational movement to the former.

3. The combination as in claim 2, and means on one of said supports for driving the screw. 105

4. A boring machine comprising a bed, a fixed bar support adjustable thereon, a spaced support also on the bed, a feed screw extending between said supports and rotatively but non-slidably attached to each of 110 them and a tail stock mounted on the bed between said supports and having a tapped hole to cooperate with the feed screw, means on one of said supports for driving the screw, and means for temporarily securing 115 the tail stock to the bed to effect an adjustment of the spaced supports and the feed screw.

5. A boring lathe comprising a bed, a head stock, a pair of spaced supports one 120 of which supports a boring bar, the supports being slidable on said bed, a screw rotatively but non-slidably attached to said spaced supports, and means for cooperating with the screw and adapted to be fixed for 125 the purpose of adjusting the spaced supports.

6. The combination with the guide ways of a machine tool, of an adjustable boring-bar unit mounted thereon, said unit com- 130

- prising a screw, a boring-bar-guiding support at one end of the screw, means supported by said guide-ways and operatively connected to the screw for driving the latter, a tail stock to which a boring bar is securable, and means operatively connecting the tail stock to the screw whereby rotation of the latter imparts translational movement to the former.
10. 7. A boring lathe comprising a bed, a head stock, a pair of spaced supports slidable on said bed, a feed screw rotatively but non-slidably attached to said spaced supports, and a tail stock between the spaced supports cooperating with the feed screw and arranged to either constitute a travelling nut and move in response to the turning of the feed screw, or to constitute a fixed nut for the purpose of adjusting the spaced supports.
15. 8. A boring machine comprising a bed, a head stock, a pair of spaced supports, slidably mounted on the base, means for fixing the supports in position, a feed screw rotatively but non-slidably attached to the spaced supports and adapted to maintain them at a fixed distance apart, a motor on one of the supports for driving the feed screw, and a tail stock slidable on the base and co-30 operating with the feed screw.
20. 9. A boring machine comprising a bed, a head stock, a pair of spaced supports slidably mounted on the base, means for fixing the supports in position, a feed screw rotatively but non-slidably attached to the spaced supports and adapted to maintain them at a fixed distance apart, a motor on one of the supports for driving the feed screw, a tail stock slidable on the base and co-35 operating with the feed screw.
25. 10. The combination as in claim 6, said means comprising a rotatable shaft which is axially movable relatively to said support.
30. 11. The combination as in claim 6, said means comprising a rotatable shaft and a clutch between the shaft and screw.
35. 12. The combination as in claim 2, said means comprising a rotatable shaft which is axially movable relatively to said supports and a clutch between said shaft and screw.
40. 13. A boring machine comprising a bed, a boring bar, a fixed bar support, a spaced support, a feed screw driving shaft, a feed screw rotatively but non-slidably connected to said spaced supports, a tail stock movable on the bed and cooperating with the feed screw, and independent driving means on one of said supports adapted to be connected to the feed screw.
45. 14. A boring machine comprising a bed, a boring bar, a fixed bar support, a spaced support, a feed screw driving shaft, a feed screw rotatively but non-slidably connected to said spaced supports and maintaining said supports in spaced relation, a tail stock movable on the bed and cooperating with the feed screw, and a driving motor on one of said supports operatively connected to the feed screw.
50. 15. A boring machine comprising a bed, a pair of spaced supports, a feed screw driving shaft below the surface of the bed, and a feed screw above the surface of the bed rotatively but non-slidably secured to the spaced supports.
55. 16. A boring machine comprising a bed, a pair of spaced supports, a feed screw driving shaft below the surface of the bed, a feed screw above the surface of the bed rotatively but non-slidably secured to the spaced supports, and gearing for connecting the sections of the feed screw together.
60. 17. A boring machine comprising a bed, a pair of spaced supports, a feed screw driving shaft below the surface of the bed, a feed screw above the surface of the bed rotatively but non-slidably secured to the spaced supports, and gearing for establishing a driving connection between said shaft and the feed screw sections arranged to permit the longitudinal movement of the shaft and screw.
65. 18. A boring machine comprising a bed, a head stock affixed thereto at one end, a tail stock slidably mounted on the bed, a boring bar affixed to the tail stock and extending toward the head stock, a support for the boring bar slidable on the bed and adapted to be affixed thereto, a second support beyond the tail stock slidable on the bed and adapted to be affixed thereto, a feed screw cooperating with the tail stock and rotatively but not slidably affixed to said spaced supports, and means on one of the spaced supports for driving the feed screw.
70. 19. A boring machine comprising a bed, a head stock affixed thereto at one end, a tail stock slidably mounted on the bed, a boring bar affixed to the tail stock and extending toward the head stock, a support for the boring bar slidable on the bed and adapted to be affixed thereto, a second support beyond the tail stock slidable on the bed and adapted to be affixed thereto, a feed screw cooperating with the tail stock and rotatively but non-slidably affixed to said spaced supports, a feed screw driving shaft extending from the head stock to the fixed bar support, and gearing between said shaft and the feed screw.
75. 20. A boring machine comprising a bed, a head stock affixed thereto at one end, a tail stock slidably mounted on the bed, a boring bar affixed to the tail stock and ex-

5 tending toward the head stock, a support for the boring bar slidable on the bed and adapted to be affixed thereto, a second support beyond the tail stock slidable on the bed and adapted to be affixed thereto, a feed screw section cooperating with the tail stock and rotatively but non-slidably affixed to said spaced supports, a feed screw driving shaft extending from the head stock to the fixed 10 bar support, gearing between said shaft and the feed screw, and independent driving means on one of said fixed supports for the feed screw.

15 21. A boring machine comprising a bed, a head stock affixed thereto at one end, a tail stock slidably mounted on the bed, a boring bar affixed to the tail stock and extending toward the head stock, a support for the boring bar slidable on the bed and adapted 20 to be affixed thereto, a second support beyond the tail stock slidable on the bed and adapted to be affixed thereto, a feed screw cooperating with the tail stock and rotatively but non-slidably affixed to said spaced supports, a feed screw driving shaft extending from the head stock to the fixed bar support, and a releasable driving connection between 25 said shaft and the feed screw.

30 22. A boring machine comprising a bed, a head stock affixed thereto at one end, a tail stock slidably mounted on the bed, a boring bar affixed to the tail stock and extending toward the head stock, a support for the boring bar slidable on the bed and adapted 35 to be affixed thereto, a second support beyond the tail stock slidable on the bed and adapted to be affixed thereto, a feed screw cooperating with the tail stock and rotatively but non-slidably affixed to said spaced supports, a feed screw driving shaft extending from the head stock to the fixed bar support, a releasable driving connection between 40 said shaft and the feed screw, and an independent driving motor on one of the 45 spaced supports operatively connected to the feed screw.

50 23. A boring machine comprising a bed, a head stock affixed thereto at one end, a tail stock slidably mounted on the bed, a boring bar affixed to the tail stock and extending toward the head stock, a support for the boring bar slidable on the bed and adapted to be affixed thereto, a second support beyond the tail stock slidable on the 55 bed and adapted to be affixed thereto, a feed screw section cooperating with the tail stock and rotatively but non-slidably affixed to said spaced supports, a feed screw driving shaft extending from the head stock to the fixed 60 bar support, a releasable driving connection between said shaft and the feed screw, and an independent driving motor on one of the spaced supports releasably connected to the feed screw.

24. A boring lathe comprising a bed, a head stock, driving means, a fixed bar support slidable on the bed and adapted to be affixed thereto, a spaced support also slidably on the bed and adapted to be fixed thereto, a feed screw section rotatively but non-slidably mounted in said spaced supports and constituting a connection between them, a tail stock slidably mounted on the bed and having a relatively fixed nut cooperating with the feed screw, a boring bar 70 extending through the fixed bar support, and secured to the tail stock, a driving feed screw shaft below the surface of the lathe and connected to the driving means at the head stock, releasable gearing between said 80 shaft and the feed screw, and a quick return feed screw driving motor on one of said spaced supports.

25 25. A boring machine comprising a fixed bar support, a tail stock for feeding the bar, a feed screw for feeding the tail stock, an intermediate bar support, and rotatable means for causing the intermediate bar support to maintain its spaced relation irrespective of the position to which the tail 90 stock may be adjusted.

26. A boring machine comprising a fixed bar support, a tail stock for feeding the bar, a feed screw for feeding the tail stock, an intermediate bar support, a nut on the feed 95 screw rotatable on the intermediate bar support, and means for driving the rotatable nut at a speed which is slower than that of the feed screw.

27. A boring machine comprising a fixed 100 bar support, a tail stock for feeding the bar, a feed screw for feeding the tail stock, an intermediate bar support, a nut on the feed screw rotatable on the intermediate bar support, and means for driving the rotatable nut at a speed which is different from that of the feed screw.

28. A boring machine comprising a fixed bar support, a tail stock for feeding the bar, a feed screw for feeding the tail stock, an 110 intermediate bar support, and means responsive to the feed screw for driving the rotatable nut at a speed which is slower than that of the feed screw.

29. A boring machine comprising a fixed 115 bar support, a tail stock for feeding the bar, a feed screw for feeding the tail stock, an intermediate bar support, and a gear slidably on the feed screw and operatively connected to the rotatable nut for driving the 120 nut at a speed which is different from that of the feed screw.

30. A boring machine comprising a fixed bar support, a feed screw, a tail stock having a complete nut cooperating with the 125 feed screw, and an intermediate screw actuated bar support between the tail stock and the fixed bar support.

31. A boring machine comprising a fixed bar support, a feed screw, a tail stock having a complete nut cooperating with the feed screw, an intermediate bar support between the tail stock and the fixed bar support, and a feed screw support connected to the intermediate bar support and movable therewith.

In witness whereof I have hereunto set my hand this 17th day of August, 1918.

ROBERT L. HIBBARD.
